UNITED STATES PATENT OFFICE

132,618

DESIGN FOR A CORRESPONDENCE CASE

Howard W. Russell, Collingswood, N. J.

Application November 10, 1941, Serial No. 104,102

Term of patent 14 years

To all whom it may concern:

Be it known that I, Howard W. Russell, a citizen of the United States, residing at Collingswood, in the county of Camden and State of New Jersey, have invented a new, original, and ornamental Design for a Correspondence Case, of which the following is a specification, reference being had to the accompanying drawings, forming part thereof.

In the drawings:

Fig. 1 is a perspective view of a correspondence case showing my new design, in a closed position viewed from the front of the same.

Fig. 2 is a similar view from the rear thereof.

Fig. 3 is a similar view of the correspondence case showing the same partly open and viewed from the front side thereof.

Fig. 4 is a similar view of the correspondence case showing the same fully opened.

I claim:

The ornamental design for a correspondence case, as shown.

HOWARD W. RUSSELL.
